UNITED STATES PATENT OFFICE.

GEORGE BERNATH, OF GARY, INDIANA, ASSIGNOR OF FIFTY ONE-HUNDREDTHS TO
NIKOLA ANTICEVICH, OF GARY, INDIANA.

BUNDLE-TIER.

1,100,945.

Specification of Letters Patent. Patented June 23, 1914.

Application filed December 26, 1913. Serial No. 808,789.

To all whom it may concern:

Be it known that I, GEORGE BERNATH, a subject of the King of Hungary, residing at Gary, in the county of Lake and State of Indiana, have invented certain new and useful Improvements in Bundle-Tiers, of which the following is a specification.

This invention relates to certain new and useful improvements in bundle tiers and has 10 for its main object the provision of a bundle tier in which a plurality of independent packages or bundles may be advantageously bound and to any of which packages or bundles access may be easily had for removal thereof without removal or disturbance of the remaining bundles or packages.

The device is more particularly adapted 20 for use in connection with the packaging of mail matter, though not confined to such use, and it has in addition to the above stated object the further object of providing a tier so constructed and arranged that a single fastening or securing means acts to tighten the tier upon all the bundles or packages 25 contained therein.

Briefly described the invention comprises 30 a skeleton case which is formed of a plurality of separate members, the present illustration embodying three members that are preferably in the form of straps or strips rather than of cords, though obviously the latter could be used. Two of these members are of identical construction and they form 35 two sides of the case and also the major portion of the ends. The remaining member constitutes the tie and is adjustably-engaged with the other two members, the strands thereof forming two of the sides of the cage as well as a part of the ends of such cage.

40 The invention will be hereinafter more fully described and then claimed, and in describing the invention in detail, reference will be had to the accompanying drawings forming a part of this specification and 45 wherein like numerals of reference will be employed for designating like parts throughout the different views of the drawings, in which:—

Figure 1 is a perspective view of a bundle 50 tier constructed in accordance with my invention, and Fig. 2 is a view in side elevation showing a plurality of packages of letters bound within the tier.

To put my invention into practice, I pro-

vide two strap members 5 and 6, the ends of 55 each member being suitably fastened together as at 7, which fastening may be of a snap-button type so as to be separable, or a permanent one, as desired. These two strap-members when the ends are fastened together 60 are in the form of oblong bands and form two sides of the case, and are provided on one side strand with spaced keepers 8, on the other side strands are similar spaced keepers 9, and on the end loops or bows of these 65 bands 5 and 6 are keepers 10. The keepers 8, 9 on the respective strands of the strap 5 are opposite to and in alinement with the keepers 8, 9 on the respective strands of the strap 6, and the keeper 10 at each end of the 70 strap 5 is opposite to and in alinement with the keeper 10 on each end of the strap 6. The remainder of the case is formed from a single strap which is of a length sufficient to pass longitudinally around the straps 5, 75 6, and twice around said straps 5, 6 transversely of the latter. This strap 11 has a buckle 12 or other suitable fastening device for its ends. It is passed first through one pair of keepers 8, then through the opposite 80 pair of keepers 9 after which it is looped together as at 14 and then passed through the keepers 10 at one end of the case and is carried around longitudinally and passed through the other pair of keepers 10 and 85 carried along the side of the case to a point in transverse alinement with the other pair of keepers 8—9 and is then looped as at 15 and carried through the keepers 9—9 and 90 8—8 and the buckle 12 or other securing device fastened. This strap thus forms a longitudinal strand for two opposite sides of the case, a transverse strand for each end of the case; and two transverse strands for each of the other two sides of the case. This 95 arrangement forms two end compartments, and a central or intermediate compartment in the case in which independent packages as 16, 17, 18 may be placed, any one of which may be removed independently of the others 100 by simply loosening the fastening 12 which will permit of the strap 11 being separated from the straps 5 or 6 so as to allow the withdrawal of the desired package. The tightening of the strap 11 obviously tightens 105 or contracts the tier throughout.

What I claim is:—

A bundle tier comprising a case formed

of a pair of spaced oblong bands, keepers carried by the longitudinal strands and by the ends of said bands, and a tightening strap passed through all of the keepers and 5 extended longitudinally around the band and transversely across the bands with its ends fastened together.

In testimony whereof I affix my signature in presence of two witnesses.

GEORGE BERNATH.
